HYDRAULIC MOTOR

Tony C. Bertoglio, Lomita, Calif., assignor of one-fourth to Robert W. Anderson, Los Angeles, Calif.

Application March 12, 1945, Serial No. 582,333

4 Claims. (Cl. 121—95)

This invention relates to a hydraulic motor and relates particularly to a motor in combination with a brush or other device which is adapted to be rotated by means of the motor which in turn is impelled by the passage of a fluid medium such as water therethrough.

It is an object of my invention to provide a simple and efficient motor for rotating a brush or other device to be rotated which motor is operated by water power.

It is a specific object of my invention to provide a motor in combination with a brush in which the brush is rotated by the motor by the passage of water through the motor and in which the water passing out of the motor is used for washing or scrubbing.

Other objects, features and advantages of my invention will be apparent to those skilled in this art as the description of my invention proceeds, particularly as taken from the accompanying drawing in which:

Fig. 1 is an elevation of the hydraulic motor shown in combination with a brush,

Fig. 2 is a vertical section of the motor taken along line 2—2 of Fig. 1,

Fig. 3 is a plan view of the motor with the cover plate removed taken along line 3—3 of Fig. 1, and

Fig. 4 is a vertical section taken along line 4—4 of Fig. 3.

Referring to the drawing, the hydraulic motor is indicated generally as 1 and a circular brush is indicated as 2 which is mounted on a shaft 3 of the motor. A water inlet hose or other flexible connection 4 is attached to the water inlet opening 4a of the motor which in turn may be connected to a suitable supply of water under pressure. The water is conducted to the water outlet or discharge outlet of the motor and issues through a pipe 5. Pipe 5 is preferably curved in order to direct the spent water on the brush to serve as a detergent liquid. If desired, the pipe 5 may be made of flexible material in order to prevent injury to the article being washed.

The motor is composed of a circular metal casing 10, the upper portion of which is recessed to receive a motor wheel 11, while the lower portion is recessed to receive a thrust bearing 30 through which the shaft 3 is extended.

The motor wheel 11 which is attached to the shaft 3 is provided with a series of substantially rectangular vanes 12a, b, c and d at suitably spaced intervals around its periphery. Each vane is fixed on a rod 14 which extends radially in a guide provided in the motor wheel to a well 15 55

recessed in the motor wheel. The end of the rod is preferably bent and the bent portion is provided with a spring 16 attached to the bottom of the well. Normally the tension of springs 16 maintain the vanes in a vertical position.

5 The interior of the casing 10 is provided with a concentric circular vane track indicated as 20 and 21. The width of the vane track is slightly larger than the width of the vanes in order to permit the vanes to slide in the vane track. The vane track has two depths; that portion of the vane track indicated as 20 extending in a clockwise direction from the water inlet opening 4a to discharge outlet 4b is of sufficient depth to receive the vanes in a vertical position while that portion of the vane track indicated as 21 extending in a counter-clockwise direction from the water inlet 4a to the discharge outlet 4b has less depth but is of sufficient depth to receive the vanes in a substantially horizontal position as shown in Fig. 4. Thus as shown more particularly in Fig. 3, vanes 12a and 12b are in a vertical position in the vane track 20 of greater depth while vanes 12c and 12d are in a horizontal position in the vane track 21 of less depth. The point 21a adjacent the water outlet 4b where the vane track 20 joins with vane track 21 is preferably inclined so that the step-up is gradual. Thus as the motorwheel is rotated, the vanes which are in vane track 20 are in a vertical position but as they pass the discharge outlet 4b, they are gradually tripped to a horizontal position by traveling on the inclined surface 21a. They then ride in a horizontal position in vane track 21 until they 25 reach the water inlet 4a whereupon the springs 16 pull the vanes to the vertical position as they enter vane track 20.

30 The vane track 21 of lesser depth is also provided with several cupped or U-shaped valves 25, which are hinged at one end at 26 and are provided with springs 27 to retain them upward in normal position. These valves are set in depressions in the lower surface of the vane track in such manner that as the vanes travel over them the valves will be forced into their depressions allowing the vanes to pass over them but when the vanes have passed over them, they will return to their normal upward positions. The cupped valves function primarily as seals to prevent the water from passing in a counter-clockwise direction to the discharge outlet. A pair of the cupped valves are provided so that when one of the valves is depressed by the passage of a vane thereover, the other will be raised to serve as the sealing medium.

The lower portion of the casing is recessed to receive a conventional thrust bearing 30 and packing 31. A plate 32 held by screws 33 holds the thrust bearing in place. A cover 34 is provided for enclosing the casing which is fastened to the casing by a number of screws 35. A gasket 36 of suitable packing material is interposed between the casing and cover in order to maintain close and water tight joints. The inner center of the cover is recessed to provide a bearing 10 for the upper end 37 of the shaft 3. A nut 38 is provided on the shaft to affix the thrust bearing against the shoulder of a circular nut 39 provided on the shaft.

In order to provide for a water tight unit and to obtain the maximum efficiency of the water pressure to rotate the motor wheel, various sealing means are used. A sealing disc 38 having a central hole to fit over the shaft is provided to cover the motor wheel. The sealing disc may be made of flexible material such as thin metal, plastic, etc. The cover plate is provided with two ridges 34a extending circumferentially on the inner surface of the plate. These ridges abut against the sealing disc. Thus, the sealing disc 34 and the ridges 34a form a seal on the upper part of the motor above the motor wheel. Also, similar ridges 11a are provided in the vertical side of the motor wheel which contact the inner casing wall 10a adjacent the motor wheel. While I have shown the inner casing wall 10a as an integral part of the casing, it may be desirable to make this wall of flexible material, such as graphite impregnated hard rubber or plastic or other self lubricating metal which may be inserted and fixed in the casing in the position shown for the wall 10a. A flexible insert of this type will have sufficient elasticity to exert a pressure against the ridges 11a. The ridges 11a acting against the wall 10a form a tight seal to prevent water pressure from releasing from the vane track through the underside of the motor wheel to the discharge outlet 4b.

Also, as stated above, the cupped valves serve to prevent water from being discharged in a counter-clockwise direction to the discharge outlet. These valves are preferably made of thin flexible metal covered with leather, rubber or other flexible material so that the force of the water pressure will force the sides of the cupped valves against the vertical walls of the vane track, thus insuring a tight seal in the vane track. In this manner, the full force of the water pressure in the space between the cupped valves and the vane adjacent the water inlet receiving the force of the water pressure such as the vane 12a shown in Fig. 3 is utilized to rotate the motor wheel.

In order to provide for a tight seal between the sides of the vanes and the walls of the vane track, the surfaces of vanes on the sides subjected to the water pressure may likewise be covered with leather, rubber, etc. If desired, the covering may be cupped shaped in the manner shown for the cupped valves so that the sides thereof will press against the walls of the vane track by the water pressure.

It will be noted that as the motor wheel is rotated, the radial swing of the vanes is merely about 45 degrees, that is each vane rotates about 45 degrees as it passes from the vertical position in vane track 20 to the horizontal position in vane track 21. Likewise, it returns the 45 degree arc when the vane is returned to the vertical position in vane track 20. A movement of more than 45 degrees is prevented by the bends at the

ends of the rods 14 since these abut against the walls of the wells when the vanes are in a vertical position thus preventing further radial movement of the vanes. Obviously, other means may be provided to limit the radial movement of the vanes.

In operation, the flexible connection 4 is connected to the outlet of a service water pipe in any known manner and the water is turned on to desired extent depending upon the speed of rotation of brush desired. The water will fill the space between a raised cupped valve and a vertical vane adjacent clockwise to the inlet opening such as for example, vane 12a shown in Fig. 3. The water pressure will exert a force against the vane causing motor wheel to rotate in a clockwise direction, bringing another vane beyond the inlet opening into the vane track 20 which in turn receives the force of the water. As the vanes pass towards the discharge outlet the water is discharged through the opening 4a and pipe 5. These vanes are then swung in horizontal position and slide in vane track 21 until they reach the opening 4a whereupon they resume their vertical positions to be again impacted with water. Thus, a steady rotation of the motor wheel is obtained which in turn rotates the brush attached to the shaft. As the water issues through pipe 5, it is directed on the brush and thus serves as a detergent liquid after it has spent its force in driving the motor. During the rotation of the motor wheel, the cupped valves 25 are alternately depressed by the passage of the vanes thereover.

It is to be understood that the foregoing description of my invention is merely illustrative thereof and is not to be taken as limiting since many variations thereof may be made without departing from the spirit thereof.

I claim:

1. A hydraulic motor comprising a substantially cylindrical casing having a water inlet opening and a discharge outlet, a motor wheel adapted to rotate concentrically in said casing, radially disposed guides in said motor wheel, a plurality of substantially rectangular vanes mounted on rods, said rods being disposed in said guides and said vanes being disposed adjacent the periphery of said motor wheel, a concentric vane track for said vanes communicating with said water inlet opening and discharge outlet and having a depth between said water inlet opening and said discharge outlet merely sufficient to receive said vanes in vertical position and between said discharge outlet and said water inlet opening merely sufficient to receive said vanes in a horizontal position, means at the ends of said rods to maintain said vanes in a normal vertical position, whereby upon rotation of said motor wheel the vanes alternately slide in the deeper portion of said vane track in vertical position and in the portion of said vane track of less depth in a horizontal position and whereby introduction of water under pressure into said vane track will exert a pressure against vertically disposed vanes thereby rotating said motor wheel, cupped valves in said vane track of less depth, said cupped valves being adapted to open upon contact with said vanes.

2. A hydraulic motor comprising a substantially cylindrical casing having a water inlet opening and a discharge outlet, a motor wheel mounted in said casing adapted to rotate concentrically in said casing, a plurality of substantially rectangular vanes mounted adjacent the periphery of said motor wheel, each vane being adapted to move

in an arc, a concentric vane track in said casing adapted to receive said vanes, the depth of said vane track from said water inlet opening to said discharge outlet being adapted to receive said vanes in a vertical position and the depth of said vane track between said discharge outlet and said water inlet opening being merely sufficient to receive said vanes in a horizontal position and valves in said last named portion of said vane track said valves being so spaced that at least 10 one of said valves is in closed position during rotation of said motor wheel.

3. A hydraulic motor comprising a substantially cylindrical casing having a water inlet opening and a discharge outlet, a motor wheel mounted in said casing adapted to rotate concentrically in said casing, a plurality of substantially rectangular vanes mounted adjacent the periphery of said motor wheel, each vane being adapted to move in an arc, a concentric vane track in said casing adapted to receive said vanes, the depth of said vane track from said water inlet opening to said discharge outlet being adapted to receive said vanes in a vertical position and the depth of said vane track between said discharge outlet and said water inlet opening being merely sufficient to receive said vanes in a horizontal position and valves in said last named portion of said vane track, said valves being adapted to be lowered into a recess in said vane track when in contact with 20 said vanes and to be raised when said vanes are out of contact with said valves and said valves being so spaced that at least one of said valves

is in closed position during rotation of said motor wheel.

4. A hydraulic motor comprising a substantially cylindrical casing having a water inlet opening at one side of said casing and a discharge outlet at the opposite side of said casing, a motor wheel mounted concentrically in said casing and adapted to rotate therein, a plurality of substantially rectangular vanes attached around the periphery of said motor wheel, a concentric vane track in said casing the width of said vane track being substantially equal to that of said vanes, the depth of that portion of the vane track between said water inlet opening and said discharge outlet in 15 one direction being substantially equal to the height of said vanes and the depth of that portion of the vane track between the discharge outlet and the water inlet opening being of less depth than the height of said vanes but being of substantial depth to receive said vanes in a substantially horizontal position, said vanes being adapted to swing radially from vertical to horizontal positions while sliding in said vane track, a pair of valves in said portion of said vane track of less depth so spaced that at least one of said valves is in closed position during rotation of said motor wheel, whereby water introduced under pressure into said vane track and exerted against vertically disposed vanes will cause said motor wheel to rotate, and means to seal said vane track to prevent water from discharging to said discharge outlet except through said vane track.

TONY C. BERTOGLIO.
